[57] CLAIM

The ornamental design for a washing machine water inlet hose, as shown and described.

DESCRIPTION

FIG. 1 is a top and front perspective view of a washing machine water inlet hose showing our new design, the hose being shown broken-away to indicate indeterminate length, and the rear being identical in appearance to that shown;

FIG. 2 is a top plan view of one end thereof;

FIG. 3 is a top plan view of the other end thereof; and FIG. 4 is an enlarged fragmentary horizontal sectional view thereof, taken along line 4—4 of FIG. 1.
